(57) **CLAIM**

The ornamental design for a display screen or portion thereof with graphical user interface of a communications terminal, as shown and described.

DESCRIPTION

FIG. 1 is a front view of a display screen or portion thereof with graphical user interface of a communications terminal; and,

FIG. 2 is a front view of a second embodiment thereof. The broken lines showing the display screen or portion thereof form no part of the claimed design. The broken lines showing portions of the graphical user interface form no part of the claimed design.

1 Claim, 2 Drawing Sheets

FIG. 1

FIG. 2
